Primary Examiner — Mitchell Siegel(74) *Attorney, Agent, or Firm* — Warner Norcross & Judd LLP(57) **CLAIM**

The ornamental design for lacrosse head, as shown and described.

DESCRIPTION

FIG. 1 is an upper perspective view of the lacrosse head embodying the new design;

FIG. 2 is a right side view thereof, the left side view being a mirror image thereof;

FIG. 3 is a front view thereof;

FIG. 4 is a rear view thereof;

FIG. 5 is a top view thereof; and,

FIG. 6 is a bottom view thereof.

FIGS. 1-6 show features of a lacrosse head in phantom lines. These features are shown for environmental purposes and do not form any part of the claimed design. The phantom lines immediately adjacent the solid-line portions of the design form the boundary of the design, with the phantom lines forming no part of the claimed design.
